UNITED STATES PATENT OFFICE

119,277

DESIGN FOR A DISHWASHING CLOTH GRIP

Bell Martin and Eva E. Hamacher, Wichita, Kans.

Application October 14, 1939, Serial No. 87,656

Term of patent 14 years

To all whom it may concern:

Be it known that we, Bell Martin and Eva E. Hamacher, both citizens of the United States, residing at Wichita, in the county of Sedgwick and State of Kansas, have invented a new, original, and ornamental Design for a Dishwashing Cloth Grip, of which the following is a specification, reference being had to the accompanying drawing, forming part thereof.

Fig. 1 is a side view of a dishwashing cloth grip showing our new design.

Fig. 2 is an end view of Fig. 1.

We claim:

The ornamental design for a dishwashing cloth grip, as shown.

BELL MARTIN.
EVA E. HAMACHER.
